Primary Examiner — Darlington Ly*(74) Attorney, Agent, or Firm* — Faegre Drinker Biddle & Reath LLP(57) CLAIM

The ornamental design for a motorcycle fuel tank as shown and described.

DESCRIPTION

FIG. 1 is a top-front-left side perspective view of a motorcycle fuel tank embodying our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines in the drawings illustrate portions of the motorcycle that form no part of the claimed design.

1 Claim, 7 Drawing Sheets(56)
